UNITED STATES PATENT OFFICE

2,130,971

ADJUSTABLE NONSLIP

Earl D. Snyder, Albany, Ill.

Application March 10, 1938, Serial No. 195,169

3 Claims. (Cl. 36—7.7)

This invention relates to a creeper or non-slip attachment for shoes particularly adapted to be worn when walking on ice although obviously capable of use where secure traction is desirable.

It is particularly aimed to provide a novel construction which is adjustable as hereinafter pointed out, to conform to shoes of different sizes, and still enable maximum flexure of the shoe as during normal use of the shoe, the device being adjustable both longitudinally and laterally, and being adapted to extend only from the forward edge of the heel portion to the ball of the foot portion.

It is further aimed to provide an exceedingly simple and inexpensive construction having novel means permitting attachment of the device to the shoe with minimum effort.

The more specific objects and advantages will become apparent from a consideration of the description following taken in connection with accompanying drawing illustrating an operative embodiment.

In said drawing:

Figure 1 is a view in side elevation, of a shoe having my attachment applied thereto;

Figure 2 is a plan view illustrating my attachment;

Figure 3 is a longitudinal sectional view through the attachment;

Figure 4 is a cross sectional view through the attachment taken on the line 4—4 of Figure 2;

Figure 5 is a cross view of the attachment taken through the forward portion, and

Figure 6 is a detail view taken on the line 6—6 of Figure 2.

Referring specifically to the drawing, the device primarily consists of a forward section 10, and a rearward section 11, connected together for longitudinal adjustment, by means of overlapping shanks 12 and 13, the former having depending flanges at 14 for guidance during adjustment as well as security against relative lateral movement, and the shank 13 having an elongated slot 15, accommodating a bolt 16 passed through an opening in the shank 12. Tightening of the nut 17 of the bolt securely fastens the sections in the desired adjusted position. The said forward section 10 is widened in advance of the shank 12 and the corners are struck downwardly at right angles to provide anti-slipping spurs 18, while the sides have curled portions or barrels 19 in which the lowermost link of side chains 20 are journaled. The side chains 20 consist of any desired number of links 21 all pivotally connected together in an obvious manner, and permitting in effect variation in the width of the forward portion of the section 10, to adapt the device to different widths of shoes.

The rearmost section 11 has a plate 22 which fits under the sole of the shoe journally designated 23, and against the breast of the heel 24 of that shoe, the end of the plate 22 extending downwardly and constituting anti-slipping spurs 25 which may be rectangular as shown, pointed or of any other desired shape.

A reinforcing bar 26 is disposed beneath the shank 13 and in abutment with the forward edges of the spurs 25 and riveted or bolted as 10 at 27 to the shank 13. Such rivet 27 also passes through a securing strap 28 disposed between the shank 13 and bar 26, which strap may be used to secure the attachment in place on the shoe, it being of leather, textile fabric or the like, and 15 being discontinuous in that it has a buckle 29 to secure the ends thereof together. This fastening strip or strap 28 it will be noted passes over the instep, around the ankle, back over the instep, through one of the links 21 at one side 20 of the device, past the sole, then directly over the foot to the uppermost link at the other side of the device after which the ends are buckled together at 29. The buckle is arranged on the outside so that in case of a surplusage of the 25 strap, there will be no undue wear on the latter.

Particular attention is called to the fact that the device extends only from the ball of the foot to the breast of the heel and that it is adjustable to different sizes of shoes and affords maximum flexing of the latter.

Various changes may be resorted to provided they fall within the spirit and scope of the invention.

I claim as my invention:

1. A device of the class described having a plate provided with depending spurs, a shank extending forwardly from the plate, a bar beneath the plate and engaging said spurs, a fastening passing through the shank and bar, and 35 a securing strap held in place between said shank and bar.

2. A device of the class described having a plate provided with depending spurs, a shank extending forwardly from the plate, a bar beneath the plate and engaging said spurs, a fastening passing through the shank and bar, a securing strap held in place between said shank and bar, a shank adjustably connected to the first mentioned shank, one of said shanks having 40 flanges overlapping the sides of the other shank, a plate carried by the second mentioned shank, 45 anti-slipping means carried by the second mentioned plate, chains at the sides of the second mentioned plate, and said securing means passing through links of said chains.

EARL D. SNYDER.
